UNITED STATES PATENT OFFICE.

CHARLES S. HURD, OF NEWARK, NEW JERSEY, ASSIGNOR TO RIKER BROS., A CORPORATION OF NEW JERSEY.

DESIGN FOR A BADGE.

No. 38,157.

Specification for Design.

Patented Aug. 14, 1906.

Application filed July 5, 1906. Serial No. 324,864. Term of patent 7 years.

To all whom it may concern:

Be it known that I, CHARLES S. HURD, a citizen of the United States, residing at Newark, in the county of Essex and State of New Jersey, have invented a new, original, and ornamental Design for a Badge, of which the following is a specification, reference being had to the accompanying drawing, forming a part thereof.

The figure is a plan view of a badge, showing my design.

I claim—

The ornamental design for a badge, as shown.

CHARLES S. HURD.
